UNITED STATES PATENT OFFICE.

DANIEL COLESTOCK, OF TITUSVILLE, PENNSYLVANIA, ASSIGNOR TO THE
TITUSVILLE IRON COMPANY, OF SAME PLACE.

DESIGN FOR A RADIATOR.

SPECIFICATION forming part of Design No. 26,592, dated February 2, 1897.

Application filed December 23, 1896. Serial No. 616,812. Term of patent 7 years.

To all whom it may concern:

Be it known that I, DANIEL COLESTOCK, a citizen of the United States, residing at Titusville, in the county of Crawford and State of Pennsylvania, have invented and produced a new and original Design for a Radiator-Section, of which the following is a full and complete specification, reference being had to the accompanying drawings, in which—

10 Figure 1 represents a front elevation of a radiator embodying my design. Fig. 2 is an enlarged horizontal section on or about line *a a*, Fig. 1.

15 The leading or characteristic feature of my design consists in a radiator-section having a series of openings 1 and 1^a, extending parallel with each other lengthwise of the section and of an equilateral or pointed arch

shape in cross-section, the openings 1 being on one side of the section and the openings 1^a directly opposite the openings 1 on the opposite side of the section. These openings begin at the points 2 (see Fig. 2) and extend inward each way in a curve to the central points 3, thereby forming a pointed arch in cross-section, the points 3 at each opposite side of the section coming very near to each other, substantially as shown in said Fig. 2.

I claim as my invention—

The design for a radiator-section, substantially as herein shown and described.

DANIEL COLESTOCK.
